HANDLE CONNECTION FOR IMPLEMENTS

Frank L. Ingling, Livingston, N. J.

Application July 21, 1934, Serial No. 736,335

4 Claims. (Cl. 306—2)

The invention relates to an adjustable handle connection for implements, such as scrubbing brushes, whereby the implement may be adjusted relatively to the handle or staff and held in 5 various adjusted positions.

The invention consists in the novel construction and combination of parts, as set forth in the appended claims.

In the accompanying drawings illustrating the 10 invention:

Fig. 1 is a side elevation of a brush equipped with the invention.

Fig. 2 is a plan view of the same.

Fig. 3 is a section, taken on the line 3—3 of

15 Fig. 2.

Fig. 4 is a section, taken on the line 4—4 of Fig. 2.

Fig. 5 is a plan view of the plate, with the connecting member broken away.

20 In these drawings the numeral 1 represents a scrubbing brush, to the back of which is attached a plate 2 having an annular series of perforations 3 constituting notches or indentations in the upper face of the plate.

25 A connecting member 4 is pivotally mounted upon the plate 2 by means of a pin 5, having a square shank engaging the member and rotatably secured in the plate 2 centrally of the annular series of notches 3. Said member has a pair 30 of opposed lugs 6 provided with notched or open-end trunnion seats 7. Member 4 may be perforated as at 8, close to the lugs 6, these perforations registering with any two of the notches 3, as the connecting member is pivotally adjusted.

35 Carried by jaws 9 of the pin 5 is a pivoted clamp 10, having a hook 11 for engaging the handle as hereinafter set forth.

Secured to and projecting beyond the end of the handle 12 are a pair of sector plates 13, having radial teeth 14 (preferably two teeth on each sector). It is preferred that the sector plates 13 be spaced apart sufficiently to fit snugly between the lugs 6 of member 4, any two of the teeth 14 being designed to register with the perforations 38 and notches 3. A pin 15 is fixed in the sector plates 13, the ends of said pin projecting laterally beyond the plates to form trunnions, engageable with the seats 7. The pin 15 is also designed to be engaged by the hook 11 of pivoted clamp 10, the engaging face of the hook being cammed, if desired.

50 It will be noted that the member 4 forms a universal joint connection between the brush and the handle, so that the brush may be adjusted in one plane about the pivot 5, and the handle

may be adjusted in a right-angular plane about the pivot 15. It will further be noted that the teeth 14, by engagement with the notches 3, secure both adjustments, the engagement being held by the clamp 10.

5

When it is desired to change the angular position of the brush with relation to the handle, or to reverse the brush, end for end, to equalize wear, the clamp 10 is released, the handle disengaged from the connecting member 4, and said member 10 is rotated until the perforations 8 register with the desired notches 3. The handle is then replaced and the clamp 10 reengaged.

The method of adjusting the angle of the handle is the same except that the connecting member 4 is not readjusted, but the handle is reengaged in a different position, so that a different pair of teeth 14 is brought into registry with the notches 3.

20 The invention provides a simple, durable article, quickly and easily adjustable to meet the conditions of the work.

I claim:

1. In an adjustable handle connection for implements, a toothed sector rigidly connected to the handle, an annularly notched plate rigidly connected to the implement, each of the notches of the plate being adapted to receive any of the teeth of the sector, a universal joint connection adapted to hold the sector and the plate in right-angular relation to each other, and a clamp adapted to secure the sector to the plate with selected teeth of the sector in registry with selected notches of the plate.

2. In an adjustable handle connection for implements, a toothed sector device rigidly connected to the handle and provided with trunnions, an annularly notched plate rigidly connected to the implement, each of the notches of the plate being adapted to receive any of the teeth of the sector, a connecting member pivotally mounted upon the plate and provided with notched lugs forming seats for the trunnions, and a clamp mounted upon the connecting member and engageable with a part of the sector device to hold selected teeth of the sector in registry with selected notches of the plate and the trunnions in registry with their seats.

3. In an adjustable handle connection for implements, a toothed sector rigidly connected to the handle, a trunnion pin secured in said sector, an annularly notched plate rigidly connected to the implement, each of the notches of the plate being adapted to receive any of the teeth of the sector, a connecting member pivotally mounted

55

upon the plate and provided with seats for the trunnion pin, and a clamp pivotally mounted upon the connecting member and having a hook engageable with the trunnion pin to hold selected teeth of the sector in registry with selected notches of the plate and the trunnion pin in registry with its seats.

4. In an adjustable handle connection for implements, a toothed sector device rigidly connected to the handle and provided with trunnions, a device including a notched plate rigidly con-

nected to the implement and notched lugs disposed at right-angles to the plate and forming seats for the trunnions, each of the notches of the plate being adapted to receive any of the teeth of the sector and a clamp pivotally mounted upon said plate device and having a hook engageable with a part of the sector device to hold selected teeth of the sector in registry with the notches of the plate and the trunnions in registry with their seats.

5
